Application February 6, 1945, Serial No. 576,480

7 Claims. (Cl. 90—14)

This invention has to do with improvements in apparatus for obtaining samples of workpieces for analysis purposes. In its more specific aspects the invention is concerned with a mechanism for obtaining the specimens at predetermined depths, for example, .005", from the surface of the work and again at another depth, for example, .010" from the surface of the workpiece at the same location. A primary aim of the invention is to provide accurate and positive acting means and equipment to enable such specimens to be taken at the selected zones, of workpieces of non-uniform thickness, which zones may be spread over a large area of the work, without rendering the piece useless or unserviceable for its intended purpose.

Heretofore random picked samples of workpieces were drilled with conventional apparatus, and specimens of the work collected and analyzed. The piece so drilled was, however, thereby rendered useless because the extent of tool penetration could not be accurately controlled and sampled pieces were rendered unfit for further use. With the present invention the extent of tool penetration is positively controlled and it is now possible to take samples of the material from every workpiece, without waste, to insure that no piece of low standard is passed.

In the manufacture of propeller blades, for example, the greatest care must be exercised in controlling the composition of the metal and the only way to make certain that a blade composition is up to the required specifications is to sample and analyze the stock in each and at several locations. With the aid of the present invention, each blade may be sampled and analyzed, and if found to be of the required metallurgical composition, passed on for final finishing operations. A main purpose and advantage of the present invention is, that by its aid, the depth of tool penetration is definitely regulated to a distance less than the thickness ordinarily allowed on a work surface for final finishing operations, e. g., grinding, and the tool marks incident to the sampling operations are removed from the piece during the subsequent operations thereon.

The ultimate aims of this invention are most satisfactorily attained if each sample taken compares in volume quite closely with other samples, which means that the surface of the workpiece from which as many as twenty samples may be taken, must at all locations, lie in a flat plane perpendicular to the sampling tool whereby the latter is caused to penetrate to a given depth uniformly on all sides. In the case of propeller

blades which are of non-uniform thickness, one of the sides is selected as the test side and the work holding fixture is so designed and related to the testing tool and depth controlling mechanism, that the test side of specimen is clamped in a fixed plane perpendicular to the axis of the testing tool, irrespective of the irregularities in contour of the opposite side. To enable such relations to be established and maintained this invention proposes in combination a work holding device that positively locates the test side of the specimen with relation to the tool in a manner that automatically equalizes the clamping pressure over that area which pressure is applied from the opposite side, notwithstanding the tapered, crowned, or otherwise non-uniform contour of that opposite side relative to the test side. By so coordinating and maintaining the test side of the work with the testing tool, workpieces of non-uniform thickness may be sampled, to a specified depth with the assurance that the bottoms of the sampled zones lie in planes paralleling the original surface and that no overcutting occurs at one side or the other that is likely to leave sharp corners or other blemishes to give rise to the developments of latent cracks or defects in the finished piece.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and in such drawings, like characters of reference denote corresponding parts throughout all the views, of which—

Figure 1 is a front view of portions of a drilling machine embodying the invention.

Fig. 2 is a vertical sectional view taken substantially along line 2—2 of Fig. 1.

Fig. 3 is a plan view of a preferred form of positive depth control shim.

Referring more particularly to Figure 1 of the drawings the invention is illustrated in connection with a machine, commonly referred to as a radial drill, which comprises a base member 18, an upstanding column (not shown) that supports a radial arm 11, on which is translatable mounted a tool head 12 that rotatably journals a tool spindle 13. The tool spindle is rotated and translated in a known manner such as more fully dis-

closed in the patent to Schauer #2,318,336. Hand levers 14 and 15 are each connected to the sleeve 52 as shown more fully in the aforesaid patent, and are optionally available to translate the spindle up or down, the former affording rapid spindle translation and the latter a relatively slow but more powerful translation.

Within the limits prescribed for the taking of samples without spoiling the work, the conventional depth dial and trip mechanisms of the standard machine are of no use whatsoever, and means have been devised, herein illustrated as a positive stop mechanism S, carried by the translatable sleeve 52 in which the spindle is journaled, and cooperating work leveling mechanism L mounted on the base 10 in fixed relation to the spindle 13 and the stop mechanism S therewith, for obtaining precision control of tool penetration to depths of but a few thousandths, in single or successive steps as may be desired.

The work leveling mechanism L comprises a framing made up of three main elements, namely, a base 16, an intermediate housing 17, and a machined frame-like cover section 18, all bolted or otherwise secured firmly together.

The end walls 19 and 20 of the housing section extend somewhat above the tops of the front and rear walls 21 and 22 forming leg standards for the cover section 18, and a substantial opening 23 therebeneath. The under surface 24 of the cover section 18 is finished true and its plane extends substantially perpendicular to the axis of the tool spindle 13, and it is against this finished under surface 24 that the workpiece is clamped during the sample taking process.

Within the housing 17, and resting normally below the openings 23, and upon upstanding studs 28^a, is located a self-equalizing work-elevating and work-clamping device. The device herein illustrated is composed of two pairs of work-shoes 25 and 26. The pair of shoes 25 are loosely pivoted at 27 to the ends of a lever 28, and the latter is pivotally mounted at a midpoint 29 to one end of a transversely extending lever 30. The other pair of shoes 26 are similarly mounted upon a lever 31 which is pivotally supported upon the other end of the transverse lever 30. The transverse lever 30 is in turn pivotally mounted, as at 32, between the end portions of a bifurcated, vertically translatable, nut element 33, and the H assembly thereby resulting, constitutes a centrally mounted self-equalizing linkage system that effectively distributes a uniform pressure through the four work shoes as the assembly is elevated off the studs 28^a into engagement with the underside of workpiece Pb. In the instant application of the invention, the workpiece Pb is a propeller blade having a tapering cross-section, and the self-equalizing action of the work shoes 25, 26 automatically compensates for the variations in thickness, and effects firm clamping of the upper side of the blade Pb against the flat under surface 24 of the top section 18 of the unit L. Roller bearing mounted rolls 34 and 35 disposed at the front and rear sides of the openings 23 initially support the propeller blade, and four guide pins 36, placed at the four corners of the work passage away between the sections 17 and 18, serve properly to guide the blade during its lateral and vertical movements.

As illustrated more clearly in Fig. 2, the nut element 33 is externally splined to a bushing 37 that is bolted to a reinforced floor 38 within the section 17, and therefore is axially shiftable but non-rotatable. Internally, the splined nut 33 is

threaded and receives the threaded portion 39 of a rotatable but non-translatable screw shaft 40. The lower end of the shaft 40 is secured to a gear wheel 41 that is supported upon thrust bearings 42 provided by a bracket 43. The bracket 43 is mounted in a fixed position to a reinforced wall 16^a of the base section, and also provides a journal bearing 44 for a hand propelled gear 45 that is meshed with the gear 41. The gear 45 is secured to a shaft 46 that extends diagonally to the outside of the frame 17 and mounts a hand wheel 47. For convenient illustration, the gear and shafts 45 and 46 in Fig. 2 are turned a slight distance away from actual position.

With the plane of the test surface of the workpiece definitely leveled and clamped, by the mechanism described, the tool spindle is lowered and the depth of penetration of the tool is positively controlled by the mechanism carried by the spindle sleeve in cooperation with the leveled surface of the clamped workpiece. A preferred form of mechanism for this purpose is illustrated in Figs. 2 and 3 and includes an externally threaded sleeve 50 that is positively locked by a supplemental rack key 51 to the conventional rack sleeve 52 of the spindle assembly. The lower portions of the sleeve 50 telescope within a flanged extension 53 whose forward end 54 extends and is adapted to engage the work surface. The extension 53 may move axially of the sleeve 50 a limited distance, the extremes of which is controlled by a pin 55 and slot 56 connection between the members. Provision may be made, as by one or more extra tapped holes 57, for changing the range of maximum shift of the extension relative to the sleeve 50. Compensation for the added weight imposed on the spindle sleeve by the stop mechanism S may if desired be made by adjusting the spindle counterbalance mechanism of the machine or by adding thereto a supplemental counterbalance mechanism. Patents #1,577,975, #1,729,583 and #2,364,318 illustrate devices that may be employed for this purpose.

The threaded upper end of the sleeve 50 carries a pair of adjusting nuts 58, between which and the flanged upper end 59 of the extension 53, a shim 60 is inserted. The nuts 58 are adjusted on the sleeve 50 to a position such that the sum of the thickness of the shim and the length of the extension 53, when the parts are compacted, will cause the end of the tool T to project beyond the work-engaging end 54 of the extension a precise distance, let us say .005". Accordingly, when the tool is advanced toward the work, penetration thereof into the work is positively stopped when the extension 53 has been moved upwardly until its flanged end 59 and shim 60 abuts the under surface of the lower of the two nuts 58. By this means tool penetration to an exact depth of .005" is assured. Fig. 1 illustrates the relation of the parts before the work is engaged, and Fig. 2, after the work has been engaged and forward tool travel definitely suspended, the latter figure illustrating in an exaggerated way the distance actually traveled by the tool beyond the end 54 of the extension, into the work.

On retraction of the tool, the chips resulting from the operation, which have been confined by the tubular extension 54, are brushed off the surface into a removable collecting pan 65 for analysis purposes and appropriately tagged.

If a specimen of the metal composition of the propeller blade is wanted from a region .005" below the surface, a shim of .005" less in thickness is substituted for the previous shim and

the tool spindle again advanced toward the work in the same location. The use of the .005" thinner shim allows the tool to travel .005" further than before, before its advance is positively stopped. A layer of stock .005" thick is thus removed, and the chips collected in another pan 66, and appropriately marked.

The herein illustrated form of shim 60, is preferably a composite of two shims, the one portion 60^a thereof being finished to a thickness .005" greater than the other portion 60^b, with a still further reduced portion 60^c intermediate the bearing portions 60^a and 60^b. The shim is formed with an elongated central opening 60^d that fits the sleeve 50 and once assembled about the sleeve, cannot fall off. With such a duplex shim on the machine it becomes a simple matter to shift it from one extreme position to the other, between successive feed movements of the tool and thereby repeatedly take samples of two constant and uniform depths from the workpiece. With the instant invention, shims of substantial body and of a wide range of thicknesses may be used.

When a number of samples are to be taken across the workpiece or over a selected area thereof, the workpiece may, of course, be shifted. However, with the invention applied to the radial arm machine herein illustrated, it is more convenient and expeditious to shift the tool head 12 and its spindle stop mechanism S to the various locations. To facilitate such re-locating of the tool, the top section 18 of the leveling unit L is formed with an elongated opening 18^a therethrough of such size as will allow substantial tool movement laterally and transversely therein thereby to enable sampling to be quickly effected over large areas of the work with but a single leveling and clamping of the workpiece.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, we claim as new and desire to secure the following combinations and elements, or equivalents thereof, by Letters Patent of the United States:

1. A mechanism for sampling workpieces combining, a non-rotatable spindle sleeve adapted to be translated vertically; a tool supporting spindle rotatably journaled in the said sleeve and movable therewith, a non-rotatable intermediate member secured to the exterior of said sleeve and provided with an adjustable abutment, a non-rotatable relatively shiftable member exteriorly mounted upon said intermediate member, said last named member having an end portion adapted to engage the surface of the work and an opposite end portion cooperatively related to the said abutment carried by said intermediate member; means for maintaining the plane of the surface of the workpiece normal to the axis of said spindle; and a shim interposed between said opposite end portion of the non-rotatable relatively shiftable member and said abutment for limiting the extent of relative movement between said shiftable member

and said tool supporting spindle at a precise point in the downward translation of the tool into the work.

2. The combination set forth in claim 1 in which the said shim is laterally shiftable and is thicker at one end than at the other.

3. A machine tool combining a rotatable spindle adapted to carry a tool; a translatable but non-rotatable sleeve journaling said spindle; spindle translating means; an abutment member carried by said sleeve, a relatively shiftable member carried by said abutment member having a portion extending beyond the spindle end adapted to engage the surface of the work and positively to stop further forward translation of the spindle when the said shiftable member reaches the end of its shift in relation to said abutment member, means for clamping a workpiece with its surface in a plane perpendicular to the line of travel of the tool; and laterally shiftable means carried by said members and interposed between said shiftable member and said abutment member for changing the limit of shift of the shiftable member a precise amount correspondingly to advance said spindle relative to the work surface a precise amount on a succeeding translation.

4. The combination of claim 3 in which said spindle sleeve is provided with rack teeth and said abutment encircles the spindle sleeve and is secured thereto by a toothed key engaging the rack teeth.

5. A machine for obtaining samples from workpieces of non-uniform thickness combining, a translatable tool spindle the combination of a translatable but non-rotatable spindle sleeve journaling the spindle; manual means for translating said spindle; a non-rotatable collar member provided with an annular abutment surrounding said sleeve; a secondary sleeve member mounted on said collar member and movable axially relative to said abutment a limited distance, one end of said secondary sleeve being adapted to engage the surface of the workpiece and operative to stop spindle translation after the tool carried by the spindle has penetrated the work a precise distance; means carried by said members and interposable between the opposite end of said secondary sleeve and said annular abutment for changing the limit of shift of said secondary sleeve to effect spindle stopping at a different precise point; and means maintaining the plane of the work surface acted upon by the tool in a fixed relation relative to the axis of the tool spindle.

6. A positive acting depth control for a tool carrying spindle having a translatable but non-rotatable spindle sleeve combining a collared member detachably connected to said non-rotatable sleeve, said collared member having an annular shoulder, a supplemental sleeve member slidable a limited distance on said member, said sleeve member having a work engaging forward end portion surrounding the tool and a flanged rear end portion, an elongated slotted spacer member surrounding said collar and disposed between said annular shoulder and the flanged end of said sleeve, said spacer member being laterally shiftable and being of greater thickness at one end than at the other and effective at one limit of shift to determine the effective length of said supplemental sleeve and at the other limit of its shift to differently determine the effective length of said supplemental

sleeve, thereby differently to control successive tool penetrations.

7. A mechanism for sampling workpieces combining, a non-rotatable spindle sleeve adapted to be translated axially; a tool supporting spindle rotatably journaled in the said sleeve and translatable therewith, an intermediate member secured to said sleeve and provided with an adjustable abutment, a relatively shiftable member mounted upon said intermediate member, said last named member having an end portion adapted to engage the surface of the work and an opposite end portion cooperatively related to

the said abutment carried by said intermediate member; and a laterally shiftable shim interposed between said opposite end portion of the relatively shiftable member and said abutment for limiting the extent of relative movement between said shiftable member and said tool supporting spindle at a precise point in the forward translation of the tool into the work, said shim normally occupying one of two effective positions and being of greater thickness in one of said positions than in the other.
